UNITED STATES PATENT OFFICE

ROBERT H. WORRALL, OF WASHINGTON, DISTRICT OF COLUMBIA, ASSIGNOR, BY MESNE ASSIGNMENTS, TO FEDERAL TELEGRAPH COMPANY, A CORPORATION OF CALIFORNIA

HARMONIC FREQUENCY SELECTOR AND AMPLIFIER CIRCUIT

Application filed November 7, 1927. Serial No. 231,590.

My invention relates broadly to signal transmission systems and more particularly to a circuit arrangement for a piezo electric crystal controlled-transmitter system.

5 One of the objects of my invention is to utilize the harmonic frequencies of a piezo electric crystal by providing a circuit arrangement for the transmission of signals at a selected frequency.

10 Another object of my invention is to select a desired harmonic frequency from a piezo electric crystal oscillator by providing a circuit arrangement for selecting this frequency and transferring the energy to a signal transmission circuit.

15 Still another object of my invention is to select and amplify a desired harmonic frequency of a piezo electric crystal controlled oscillator by providing a practical circuit arrangement for selecting and amplifying this frequency for the transmission of signals.

20 Other and further objects of my invention reside in the circuit arrangement for a piezo electric crystal controlled transmitter, as 25 more fully described in the specification hereinafter following by reference to the accompanying drawings wherein:

Figure 1 is a diagrammatic circuit arrangement of the piezo electric crystal controlled transmitter circuit of my invention illustrating the principles of my invention; Fig. 2 shows a modified coupling circuit arrangement for the piezo electric crystal controlled oscillator and power amplifier circuit of my invention; and Fig. 3 shows one of the circuits which I may employ in the power amplifier and oscillator system for controlling regenerative action in the tube circuits of the transmitting system.

40 By reference to Fig. 1 of the drawings it will be seen that the crystal control circuit consists of the following: electron tube 1, the quartz crystal 2, a grid leak 3, primary winding 4 of transformer 5 and a by-pass 45 condenser 6 connected in the proper manner to batteries 7 and 8. Coupled to primary winding 4 of the crystal circuit is the frequency selector and amplifier circuit 9 which consists of an inductance 10 tuned by a variable condenser 11, a grid condenser 12, and

a grid leak 14 in the input circuit of power amplifier tube 15. The output circuit includes a balancing condenser 16, a radio frequency choke 17, a blocking condenser 18 and an inductance 19 tuned by the condenser 20 connected to a transmitting tube 15 and a power source in the proper manner. The antenna circuit 21 may consist of any of the many types of inductive or direct coupled circuits coupled to the coil 19 by means of inductance 22.

55 The quartz crystal 2 is so chosen that its harmonics fall close enough together to give a sufficient number of different operating frequencies. Coil 4 is of such a value that the 60 crystal will oscillate and at the same time the circuit will contain the required harmonics. The grid leak 3 or any method of grid bias control assists in maintaining the grid at the proper operating potential.

65 The harmonics are transferred through the medium of inductive coupling to the inductance 10, the circuit consisting of coil 10 and condenser 11 constituting the grid circuit of the power amplifier. The circuit 9 may be 70 tuned to any multiple of the crystal fundamental, and the same multiple frequency amplified by tuning the plate circuit of tube 15 which includes the coil 19 and the condenser 20. The condenser 16 acts as a balancing 75 condenser, and a regeneration or degeneration control, that is, the condenser 16 may also be used as a control device for governing the excitation of the antenna 21. The grid circuit 9 may also be tuned to the crystal fundamental 80 and any multiple of the fundamental may be amplified by tuning the plate circuit. The grid circuit may also be tuned to any multiple of the fundamental, and any multiple of this 85 multiple may be amplified in the plate circuit previously described and transferred to other amplifiers for further power amplification and thence to any antenna or to the antenna system as shown at coil 22 and condenser 23.

90 This process of amplification may be continued to tubes of the largest power through the medium of any type of amplifier circuit suitable for the frequency and power and 95 thence to the antenna system.

Fig. 2 illustrates another method of achieving the results set forth in Fig. 1, except in this case direct coupling is used for the transfer of the harmonics from the crystal circuit 5 to the grid circuit of the power amplifier.

Condenser 12 is made variable and serves both as a coupling device and as a tuning control between the output circuit of the oscillator and the input circuit of the power amplifier. The plate circuit inductance 4 is provided with a slidable connection at 24 which extends to coupling condenser 12. The opposite end of inductance 4 is connected through condenser 25 with the opposite side 15 of the input circuit of the power amplifier. Tuning condenser 11 is connected across inductance 4 for facilitating the selection of a harmonic frequency of crystal 2.

Fig. 3 illustrates a modified coupling circuit arrangement which contains the piezo electric crystal controlled oscillator and the power amplifier, whereby a harmonic frequency may be produced and radiated from the antenna system. In the several modified 25 circuits, I may employ either series or parallel feed for the plate supply system but for the purpose of simplicity I have illustrated series feed.

Among the advantages arising out of the 30 circuit arrangements of my invention, there is the ability of the circuit system to develop weak harmonics in the inductance 4 and permit these harmonics to be transferred to a power amplifier system and amplified for 35 transmitting purposes. The transmitting circuits may be shifted from one harmonic frequency to another without touching or changing the piezo electric crystal 2.

The advantage of the harmonic frequencies and selection of a particular frequency 40 may be effected through the medium of two electron tubes in the circuit arrangements shown, and the selected and amplified harmonic frequency is made available for trans- 45 fer to any number of stages of additional amplification for placing the energy in proper condition for radiation and transmission of signals.

While I have described my invention in 50 certain preferred embodiments, I desire that it be understood that modifications of my invention may be made and that no limitations upon my invention are intended other than are imposed by the scope of the appended 55 claims.

What I claim as new and desire to secure by Letters Patent of the United States is as follows:

1. A frequency selector and amplification 60 system comprising an electron tube for generating high frequency oscillations, a piezo electric crystal connected to said electron tube for stabilizing the frequency of said electron tube, circuits connected to the output of 65 said electron tube for selecting a harmonic

frequency of the fundamental frequency of said piezo electric crystal, and connections between the output circuit of said electron tube and another electron tube effecting an increase in amplitude of the harmonic frequency thus selected. 70

2. In a transmitter system, the combination of a signal transmission circuit, a piezo electric crystal element, an electron tube having input and output circuits, the input circuit of said electron tube connected to said piezo electric crystal element, said electron tube having means connected into its output circuit for selectively and independently sustaining a plurality of harmonics of the fundamental frequency of said piezo electric crystal element, an amplification system, a tuned circuit coupling said amplification system with said aforementioned means and adjustable to selectively amplify any one of the harmonic frequencies of said piezo electric crystal element selected and sustained by said aforementioned means, and connections between said amplification system and said transmission circuit for impressing the selected harmonic frequencies of increased amplitude upon said transmission circuit. 80 85 90
